AUTOMATIC OVERFLOW CONTROL

Filed June 23, 1931

INVENTOR.

FREDERICK O. JOHNSON.

BY.

H. P. Duckman

ATTORNEY.

UNITED STATES PATENT OFFICE

FREDERICK O. JOHNSON, OF LONG BEACH, CALIFORNIA

AUTOMATIC OVERFLOW CONTROL

Application filed June 23, 1931. Serial No. 546,194.

This invention relates to an automatic overflow control whereby a tub of water is prevented from running over if the faucet is accidentally left open.

5 **65** An object of my invention is to provide a novel means whereby the flow of water into the tub is automatically stopped when a predetermined height of water has been drawn into the tub.

10 **70** Another object is to provide a device of the character stated which is attachable to the present well known type of plumbing fitting used in modern bathroom installations.

15 **75** A feature of my invention resides in the automatic closure of a valve when the water has reached a predetermined height and then over-flows into a trip chamber.

Still another object is to provide a novel 20 tripping means actuated by the weight of water in a tube which acts to operate a quick closing valve and thus shut off the supply of water.

Other objects, advantages, and features of 25 **80** invention may appear from the accompanying drawing, the subjoined detailed description and the appended claims.

In the drawing

Figure 1 is a front elevation of my automatic over-flow control.

Figure 2 is a fragmentary, transverse, sectional view of the same.

Figure 3 is a fragmentary side view of the tripping mechanism and the trip setting means.

Referring more particularly to the drawing, the numeral 1 indicates a tube stand which is positioned adjacent to the tub and at one end thereof, all in the usual and well known manner understood by those skilled in the art. A fitting 2 extends into the lower end of the tube stand 1 and opens into the tub in the bottom thereof. This fitting serves to drain the tub as will be further described,

40 **85** and as the water rises in the tub, it will also rise in the tube 1 for a purpose to be further described. The usual hot and cold water faucets 3—4 are mounted on a bracket 5, and supply water to the main supply pipe 6. A quick closing valve 7 is mounted in the sup-

ply pipe 6 and the details of this valve will be further described. A fitting 8 is attached to the upper end of the tube 1 and this fitting is also provided with an outlet tap 9 to which a faucet of usual and well known design is secured, and thru which the water pours into the tub.

A sleeve 10 is slidably mounted in the tube 1 and when this sleeve is lowered, it rests upon a seat 11 and prevents the water from draining out of the tub. As the water rises in the tub, and also in the tube 1, it may flow over the top of the sleeve 10 and thus drain out of the tub, but this drain is sufficient to prevent the tub from over-flowing when the faucets 3 or 4 are turned on the full amount. The tub would continue to fill and would eventually over-flow unless the supply of water is stopped.

70 **90** The sleeve 10 is raised and lowered manually by means of a shaft 12 which extends out of the top of the tube 1. The shaft 12 is attached at its upper end to a U-shaped link 13, and this link is actuated by the following mechanism: A casting 14 is secured to the link 13 and the casting is provided at its upper end with a plate 15. A cam 16 is secured to the inner end of a shaft 17 which shaft is rotated by the handle 18. It will be evident that as the handle 18 is rotated, the cam 16 will move the casting 14 upwardly to raise the sleeve 10 or on further rotation of the handle, the sleeve will be lowered upon its seat.

75 **95** A cylinder 19 is mounted adjacent to the tube 1, and a drain pipe 20 extends from the bottom of the cylinder 19 into the fitting 2 so that water will drain out of the cylinder into the sewer.

A basket 21 is slidably mounted in the cylinder 19, and this basket is provided with a small drain hole 22 in the bottom thereof. This drain hole is not sufficiently large so as to materially effect the movement of the basket when water pours into the top of the same, but merely acts to gradually drain the water therefrom after the water from the main supply has been stopped, as will be further described. The basket 21 is open at the top and water is admitted into the cylin- 100

der 19 thru a collar 23 which encircles the tube 1 and is attached to the top of the cylinder 19.

A port 24 extends from the tube 1 thru the 5 collar 23 and thence into the top of the cylinder 19. The port 24 is below the top of the sleeve 10 so that water will pour into the cylinder 19 before it starts to drain over the top of the sleeve. As the water pours into 10 the cylinder 19, it will fill the basket 21, thus materially increasing the weight of the basket and will therefore urge the same downwardly.

A wire or cable 25 is attached to the basket 15 21 and extends upwardly thru the collar 23. The wire is secured at its upper end to a lever 26 which lever is pivotally mounted on an arm 27 which rises from the fitting 8. A counter-weight 28 is adjustably mounted on 20 one end of the lever 26 and the purpose of the counter-weight is to slightly over-balance the weight of the basket 21 when empty.

A roller 29 is mounted on the lever 26 for 25 the purpose of holding the quick closing valve 7 open, in the following manner: A stem 30 extends from the valve 7 and a cam disc 31 is firmly secured to the outer end of the stem. The disc is provided with a shoulder 32 which engages the roller 29 and thus 30 holds the disc against movement in counter clock-wise direction, as viewed in Figure 3. The disc is urged in counter clock-wise direction by means of a spring 33 which is suitably attached to the disc.

35 A coupling rod 34 is attached to the disc 31 at its lower end, and to the link 13 at its upper end. This rod is preferably made adjustable as to length so that the disc 31 will be rotated a proper amount in a clock-wise direction 40 when the link 13 is moved upwardly. When the handle 18 is operated to raise the sleeve 10 and drain the tub, this same movement will rotate the disc 31 thru the medium of the rod 34 and the counter-weight 28 will swing 45 the lever 26 on its pivot and will cause the roller 29 to engage the shoulder 32.

The spring 33 is now in tension. When the disc 31 is in the position shown in Figures 1 and 3, the valve 7 is open to permit water to 50 flow into the tub.

When it is desired to fill the tub with water, the handle 18 is rotated and the sleeve 10 is lowered upon the seat 11. The rod 34 is slidably attached to the disc 31 at its lower end 55 and thus said rod can move downwardly without disturbing the cocked position of the disc. The water faucets 3 or 4 are now opened, and water flows thru the intake pipe 6 and into the tub thru the tap 9. When the water 60 starts to flow thru the port 24, the basket 21 is filled and the additional weight of the water overcomes the counterweight 28 and the lever 26 is swung on its pivot to move the roller 29 from under the shoulder 32. The spring 65

33 then acts to rotate the disc 31 and the shaft 30 which closes the quick acting valve 7.

In order to drain the water from the tub, the handle 18 must be again rotated to raise 70 the sleeve 10, and this action will again open the valve 7 and cock the disc 31 as previously described.

Having described my invention, I claim:

1. An automatic over-flow control comprising an intake pipe, a valve in said pipe, means 75 engaging the valve whereby the same is held open, means urging the valve into closed position, a cylinder, a basket in said cylinder, liquid intake means into said cylinder whereby the basket is filled, and means extending from the basket to the means holding the valve open, whereby said holding means is released when the basket is filled.

2. An automatic over-flow control comprising an intake pipe, a valve in said pipe, a stem 80 extending from the valve, a disc secured to said stem, spring means engaging the disc to urge the valve to closed position, means engaging the disc whereby the valve is held in open position, a cylinder, a basket in said cylinder, water intake means at the upper end of said cylinder whereby water is admitted into the basket, and means extending from the basket to said first named means whereby the first named means are released to permit 85 closing of said valve.

3. An automatic over-flow control comprising an intake pipe, a valve in said pipe, a stem 90 extending from the valve, a disc secured to said stem, spring means engaging the disc to urge the valve to closed position, a lever pivotally mounted adjacent said disc, a shoulder on the disc, a roller on the lever engaging said shoulder whereby the valve is held in open position, a cylinder, a basket in the cylinder, water intake means at the top of said cylinder whereby water is admitted into the basket, a wire extending from the basket to the lever whereby the lever is swung on its pivot to release the roller from under said shoulder whereby the valve is urged into closed position by said spring means.

4. An automatic over-flow control for bath tubs and the like, comprising a tube, a drain fitting at the lower end of said tube into which water passes from the tub, a drain sleeve seated in said fitting, a shaft rising from the top of the sleeve, manual means to which said shaft extends whereby the shaft and sleeve 105 are raised and lowered in the tube, a cylinder, a basket in said cylinder, a collar surrounding said tube and attached to said cylinder, said collar having a port therethru thru which water flows into the basket, an intake pipe, 110 a valve in said pipe, a stem extending from the valve, a disc on the stem, lever means engaging said disc whereby the valve is held in open position, a wire extending from said lever means to said basket, spring means en- 115

gaging said disc whereby the valve is urged to closed position, and means extending from said disc to said sleeve actuating means whereby said disc is rotated and the valve is opened when said sleeve actuating means are manipulated.

In testimony whereof, I affix my signature.
FREDERICK O. JOHNSON.
